UNITED STATES PATENT OFFICE.

HENRY T. SMITH, OF UMATILLA, FLORIDA.

SHOE.

SPECIFICATION forming part of Letters Patent No. 537,492, dated April 16, 1895.

Application filed January 31, 1895. Serial No. 536,857. (No model.)

To all whom it may concern:

Be it known that I, HENRY T. SMITH, a citizen of the United States, residing at Umatilla, in the county of Lake and State of Florida, have invented a new and useful Shoe, of which the following is a specification.

My invention relates to shoes and has for its object to provide a boot or shoe for the use of laborers, as fruit-pickers, &c., such shoe being constructed with a metallic sole and heel to avoid the rapid wearing to which similar devices constructed of leather are subject; and the object in view is to provide a metallic protector which shall not exceed, in weight, an ordinary leather shoe adapted for the same purpose; and furthermore, to provide means for replacing worn parts.

Further objects and advantages of this invention will appear in the following description, and the novel features thereof will be particularly pointed out in the appended claims.

In the drawings: Figure 1 is a side view of a shoe constructed in accordance with my invention. Fig. 2 is a longitudinal section of the same. Fig. 3 is a detail view, in perspective, of the sole and heel, with the removable heel-plate detached.

Similar numerals of reference indicate corresponding parts in all the figures of the drawings.

1 designates a metallic sole, having a concaved upper surface and adapted to be covered, on its inner surface, to protect the foot of the wearer, by a thin layer of leather, as shown at 2, and integral with this sole-plate, at its rear end, is the heel 3, which is hollow, being recessed as shown at 4. In this recess are formed bosses or enlargements 5, provided with sockets 6 for engagements by screws 7 for holding the removable heel-plate 8 in place. These bosses or enlargements 5 terminate short of the plane of the lower edge of the heel proper, and the heel-plate is provided, upon its upper surface, with a rim 9, to fit in the cavity 45 of the heel, the outer edge of said plate being flush with the outer surface of the heel. The screws by which the heel-plate is held in place have their heads countersunk in the outer surface of the plate, said screws being short 50 to avoid unnecessary weight, whereby they

engage the sockets in the bosses or enlargements throughout only a portion of the length of such sockets, as shown clearly in Fig. 2.

Rising from the rear end of the sole-plate, and flush with the rear side of the heel, is a 55 counter or guard 10, corresponding in general shape with an ordinary shoe or boot counter, and being separated from the foot of the wearer by the leather upper 11. The sole-plate is secured to the vamp and quarters of 60 the shoe by means of pegs, tacks, or other similar devices in use, and the guard or counter is provided with a series of perforations 12 connected by a groove 13, for stitching 14, such stitching being, preferably, of copper 65 wire or its equivalent.

By constructing the device of thin metal, and with a hollow heel, it may be made of sufficient lightness to be worn with ease, and when the heel-plate becomes useless by reason 70 of long wear, it may be replaced in the manner hereinbefore indicated.

The object in extending the sole-plate, especially in shoes adapted for use by fruit-pickers and other laborers who are required 75 to climb ladders, is to receive the wear of the rungs of the ladder, which usually occurs upon the portion of the sole just in advance of the heel. The under surface of the sole-plate is preferably roughened, as shown in the 80 drawings.

It will be understood that while I have described my invention as applied to a workman's shoe, it is equally applicable to dress or fine shoes for gentlemen and ladies and also 85 for children, the only difference being in the weight or thickness of the parts which would naturally be greater for a heavy than for a light shoe, and in light or dress shoes the roughening of the lower surface of the sole 90 may be omitted, as the main object of this portion of the construction is to enable the wearer to obtain a firm foothold upon the surface traversed.

Various changes in the form, proportion, 95 and the minor details of construction may be resorted to without departing from the spirit or sacrificing any of the advantages of this invention.

Having described the invention, I claim— 100

In a shoe, a protecting device having a sole-plate adapted to be secured to the vamp and quarters and extending approximately to the front end of the shoe, an integral hollow heel provided with threaded sockets, a removable heel-plate provided with a rib to fit within the cavity of the heel and secured in place by countersunk screws engaging said sockets, and a guard or counter integral with said sole-

plate and heel and provided with perforations 10 for stitching, substantially as specified.

In testimony that I claim the foregoing as my own I have hereto affixed my signature in the presence of two witnesses.

HENRY T. SMITH.
